Patent expires April 5, 1963

16 Claims. (Cl. 230—123)

1

This invention relates to compressors, pumps, turbines, and like rotary power conversion machines, operating with compressible viscous fluids, and more particularly to the blading of axial flow stages of such machines.

An object of the invention is to provide blades appropriately shaped in regard to their leading angle, trailing angle, chord angle and aerofoil profile to conform to a possible and stable fluid flow pattern. Other objects of the invention are to provide blading conforming to or/and imposing on the fluid a flow pattern having one or more advantageous characteristics as hereinafter set forth or/and to provide blading whose geometrical properties facilitate manufacture.

In the design of blades for such machines various empirical and arbitrary laws have been proposed to which the designs of blades are to conform, but with the exception of one type of blading, hereinafter referred to as "free vortex" blading, the blade shapes so developed may and frequently do postulate fluid flow patterns which are either impossible because they do not satisfy necessary conditions of continuity or equilibrium, or, alternatively are unstable.

It has been pointed out in Whittle U. S. Patent 2,378,372 that the characteristics of the flow from a stator nozzle ring of a turbine, or the discharge from the rotor of an axial flow compressor, tend to approximate to the characteristics of a free vortex and the said specification describes and claims blades which are shaped to conform to such a vortex flow pattern at entry and discharge; and such blades are known as "free-vortex" blades and will hereinafter be so referred to.

I have found, however, that it is possible to design blades which satisfy the condition of conforming to a stable flow pattern which can actually exist in the machine, to a sufficient degree of approximation for practical purposes, otherwise than by designing to the "free-vortex" shape as set out in the above-mentioned patent specification No. 2,378,372 provided that the blade shape satisfies certain other requirements to be hereinafter set forth; and that these requirements give sufficient latitude to the designer to satisfy at least some of a number of other possible requirements concerned more especially with the aerodynamic characteristics of the blades or of the machine in which they are incorporated and such matters as ease of manufacture.

According to the present invention, a row of blades in a rotary power conversion machine of the type herein first referred to, comprises individual blades so shaped, (in respect of the radial

2

distribution of their leading and trailing angles) as to conform to a radial distribution of entry and discharge velocities of the working fluid, such that the difference of the whirl velocities, at entry and discharge respectively of the blade row in question, is in inverse proportionality to the radial distance from the rotational axis of the machine, but excluding blades of the "free-vortex" form as hereinbefore defined.

The invention also includes compressors, pumps, turbines and like rotary power conversion machines operating with compressible viscous fluids and comprising a single row of rotor blades or rows of rotor blades rotating at the same or different speeds in the same or different directions with or without one or more rows of stator or stationary blades; wherein the blades of at least one row of blading, constituting or forming part of, an axial flow stage, are shaped as set forth in the preceding paragraph.

It will be seen that this does not imply that the actual whirl velocity at entry or at discharge necessarily follows the law of inverse proportionality to the radial distance as is the case with free vortex blading, but it is only the increment (positive or negative) of whirl velocity acquired by the fluid in passing through the blading row, which satisfies the law of inverse proportionality to the radial distance. Free vortex blading does, however, satisfy this last named law and would, if it were not herein specifically excluded, constitute a limiting case of blading in accordance with this invention.

In amplification of the foregoing statement, the leading and trailing angles of the blade are defined by the tangents to the centre line of the blade profile at the leading and trailing edges, and the blade is said to "conform" to the (assigned) entry and discharge velocities, if the entry is without shock and the trailing angle of the blade is substantially the same as the discharge angle of the fluid.

Entry without shock is obtained if the leading angle of the blade is within 10° of the fluid entry angle (averaged over the circumference of the blade row), though for turbine blades, especially reaction blades, substantially shockless entry is obtained with somewhat greater departures of the blade leading angle from the fluid entry angle.

Further, any assigned distribution of fluid velocities must satisfy the well known velocity triangle relations and the axial components of these velocities must satisfy the condition of continuity of flow.

To recapitulate, blading in accordance with this

invention and constituting a row of rotor or stator blading will be so shaped as substantially to satisfy the following condition, viz:

The blades conform (as herein defined) to some possible assigned distribution of fluid velocities at entry and discharge (of the blade row considered) in which the difference between the whirl velocities at entry and discharge respectively is in inverse proportionality to the radial distance from the axis of rotation; but the absolute whirl velocities at entry to and discharge from the blades are not in inverse proportionality to the radial distance as with free vortex blades.

As will hereinafter be shown, the satisfaction of this condition does not uniquely determine the shape of the blade, but allows some latitude in the design. When one blade row only is under consideration, the radial distribution of any one of the following parameters, viz: entry angle, discharge angle, and chord angle (namely the angle between the axial direction and a line joining the leading and trailing edges of the blade at the same radial distance from the axis of rotation), may be selected to fulfil some particular design requirement; or, when two consecutive blade rows are considered, the radial distributions of any two of the three pairs of the above-mentioned parameters may be so selected. The particular design requirements, as yet unspecified, to be satisfied by the above-mentioned selection will be more fully discussed hereinafter.

Figure 1 is a diagram of the blades of an axial flow machine according to this invention.

Figure 2 is a velocity diagram corresponding to the blading of Figure 1.

Figure 3 is a diagram illustrating radial distribution of velocities over a blade according to this invention.

The invention is explained graphically with the aid of the accompanying diagrams relating to a stage which is taken to consist of two adjacent blade rows, whether rotor or stator or both rotors. Figure 1 diagrammatically illustrates the two blade rows 1 and 2 at any radius r , the actual blading shown being of the type used for axial compressors. 3 and 4 are the leading edges of the blades in rows 1 and 2 respectively while 5 and 6 are the respective trailing edges of the blades. The axial direction of flow is indicated by the arrow 7. The dotted blade row 8 is the previous blade row, if existing, to the first row considered. The peripheral velocity of the first blade row, second blade row and previous blade row are denoted by U_1 , U_2 and U_0 respectively and are positive if taken in the direction of the arrows shown in Fig. 1. If any blade row is stationary then the corresponding U value is zero. The angles A, B, C, D and E in Fig. 1 denote the direction of the fluid relative to the blades at outlet from the previous row, inlet to first row, outlet from first row, inlet to second row, and outlet from second row respectively; all the angles being measured from the axial direction. The chord angle will be measured from the axial direction, the angle being positive for the arrangement shown in Fig. 1.

The velocity triangles corresponding to the blade rows of Fig. 1 at any radius r are shown in Fig. 2, where W_1 , W_2 and W_3 are respectively the axial components of the velocities before the first row 1, before the second row 2 and after the second row 2, V_A , V_B , V_C , V_D , and V_E are the fluid velocities relative to the blades at inlet and outlet corresponding to the fluid angles A, B, C, D and E respectively. The peripheral velocities

U_0 , U_1 , U_2 , are represented by the lengths PQ , RQ , and RS , respectively and the absolute fluid velocities are represented by chain-dotted lines. From these velocity triangles it can easily be proved by geometry that

$$U_0 + U_1 = W_1 (\tan A + \tan B) \quad (1)$$

$$U_1 + U_2 = W_2 (\tan C + \tan D) \quad (2)$$

also V_A , V_B , V_C , V_D and V_E are respectively equal to $W_1 \sec A$, $W_1 \sec B$, $W_2 \sec C$, $W_2 \sec D$ and $W_3 \sec E$. Again the work done per unit mass of fluid for the first blade row is equal to U_1 multiplied by the change in the circumferential components of the absolute fluid velocities between inlet and outlet of the blade row so that this work done is given by

$$U_1 \times (U_1 - W_2 \tan C - U_1 \tan B) = \frac{U_1 \times (W_1 \tan B - W_2 \tan C)}{2} \quad (3)$$

Similarly for the second row the work done per unit mass is equal to

$$U_2 \times (W_2 \tan D - W_3 \tan E) \quad (4)$$

In considering an actual design, it is usual to fix on a design radius r_d and to assume that the values of the peripheral velocities U_0 , U_1 and U_2 , the axial velocity components W_1 , W_2 and W_3 , the work required to be done in each blade row and the outlet angle A from the previous blade row, are known. The four unknowns left at this radius would then be the angles B, C, D and E and these angles can be determined by making use of the two velocity triangle Equations 1 and 2 and the two work done Equations 3 and 4 of the previous paragraph. From tests of blades in cascade, which are well known to blade designers, it is possible to pick on the blade profiles which when appropriately spaced and placed at the correct chord angle will satisfy the above fluid outlet angles C and E and the condition of entry without shock as previously defined.

Having determined the blading at the design radius r_d , it remains to evaluate the corresponding radial distributions of angles and velocities. At any other radius r , in a similar manner to that at the design radius, there will be the two velocity triangle equations coupled with two other equations, one for each row satisfying the condition constituting the basis of this invention, viz:

$$(W_1 \tan B - W_2 \tan C)r = \text{const.} \quad (3a)$$

$$(W_2 \tan D - W_3 \tan E)r = \text{const.} \quad (4a)$$

There are thus four equations in all containing eight unknowns, viz. the five angles A, B, C, D and E and the radial distributions of the axial velocities as defined by the ratios of W_1 , W_2 and W_3 to their respective values at the design radius. The eight unknowns are reducible to six by stipulating that the radial distributions of all three axial velocity components W_1 , W_2 , W_3 are the same, i. e. that at any given radius

$$\frac{W_1}{W_{10}} = \frac{W_2}{W_{20}} = \frac{W_3}{W_{30}}$$

where W_{10} , W_{20} , W_{30} , are the values of the axial velocity components at the "design" radius. It will be seen that this stipulation does not define the actual radial distributions of the axial velocity components. This leaves two radial distributions which can be arbitrarily defined. Now the velocities relative to the blades and the geometry of the blading are directly connected with the angles A, B, C, D and E and the radial distribution of the axial velocities, so that the shapes of the blades for the two rows of a stage designed according to

5

this invention will be finally and completely defined by selecting the radial distributions of any two of the following variables, viz: the absolute or relative fluid velocities at inlet and outlet, the axial components thereof, and the angles of fluid flow (absolute or relative to the blades) at inlet or outlet, (or the entry and discharge angles of the blades): alternatively, geometrical properties of the blade shapes may be selected which determine by implication the radial distribution of any two of the above-mentioned variables. Further, both the selected variables may be associated with one blade row or one may be associated with one blade row and the other with the other blade row.

Though the method of design given will apply to any desirable radial distribution of the axial components of the fluid velocities, it is normally convenient to consider either a constant or parabolic radial distribution, the latter distribution being appropriate for taking into account boundary layer and secondary effects. When using a parabolic distribution the velocities chosen at the blade ends in the boundary layer are preferably not zero as such a distribution requires poor blade profiles at points located in the boundary layers. It is better to design to a radial distribution which fits more closely to the ideal conditions over the greater part of the blade height and then finishes with finite velocities at the blade ends.

An example of such a parabolic distribution is shown in Fig. 3 where the axial component of velocity W is plotted in the direction θ between the bounding walls 10 and 11 of the annular passage through which the fluid flows in a compressor or turbine. The selected W distribution is indicated by the curve 12 and its mean value by the line and arrow 13. Arrows 14 and 15 indicate the maximum and minimum values of W respectively. For parabolic distributions it can easily be proved that

$$W_{\text{minimum}} = 3W_{\text{mean}} - 2W_{\text{maximum}}$$

The values of $W_{\text{mean}}/W_{\text{maximum}}$ which appear desirable to use are normally between 0.85 and 0.95 for compressors and between 0.9 and 1.0 for turbines.

For flows which are incompressible or only slightly compressible the fluid velocity gives a good criterion for detrimental effects with especial reference to cavitation. When however velocities become large and the flow is highly compressible, the local Mach number is a better criterion having regard especially to detrimental compressibility effects. The Mach number is defined as the velocity relative to the blade at the point considered divided by the local acoustic velocity. The local acoustic velocity will generally vary radially but its radial variation can be neglected for the slightly compressible flows. Radial distributions of velocity and Mach number will be hereinafter specified to define typical blade forms according to this invention.

It will be clear that the ability to select two out of six independently variable quantities (either directly or by specifying geometrical blade properties implicitly determining said radial distributions), while complying with the necessary requirements of continuity of flow and velocity triangle relationships and also with the basic requirement of this invention formulated in Equations 3a and 4a, offers to the designer a very wide choice of possible blade forms.

In what follows, certain desirable design characteristics and their influence on this selection will be further discussed, but before doing so it

6

will be convenient to describe in detail, by way of example, one typical embodiment of the invention as applied to a single, axial flow, compressor stage, consisting of a row of rotor blades followed and preceded by rows of stator blades, all as illustrated in Figs. 1 and 2. It will therefore be seen that

$$U_0 = U_2 = 0$$

The following design data are postulated:

Inside radius (for each row) ____ inches ____ 6

Outside radius (for each row) ____ do ____ 8

R. P. M. ____ 10,000

Rate of doing work on the fluid

H. P. per lb. of fluid ____ 9.3

Mean axial fluid velocity for each row,

ft./sec ____ 450

Whirl velocities at outlet of both stator rows, at the inside radius, are zero, so that, at this radius,

$$\tan A = \tan E = 0$$

The "selected" radial distributions are:

(1) Axial fluid velocity is constant along the radius: hence,

$$W_1 = W_2 = W_3 = 450 \text{ ft./sec. at all radii}$$

(2) To reduce compressibility effects on the second stator blade row, the inlet fluid velocity of that row is constant along the radius, i. e.

$$\tan D = \text{const.}$$

Taking the inside radius as the design radius r_d , the computed value of $\tan B - \tan C$ which will give the required work done in the rotating blade row 1 is 0.70.

The following table gives the data for the blading of the example.

Reference Radius	6"	7"	8"	Obtained from--
U_1 ft./sec	525	612.5	700	
$W_1 = W_2 = W_3$ ft./sec	450	450	450	Arbitrary Selection.
$\tan A - \tan B$	1.167	1.361	1.555	Velocity triangle relations.
$\tan C - \tan D$	1.167	1.361	1.555	Velocity triangle relations.
$\tan B - \tan C$	0.700	0.600	0.525	Equations 3a, 4a.
$\tan D - \tan E$	0.700	0.600	0.525	Equations 3a, 4a.
$\tan A$	0	0.100	0.175	
$\tan B$	1.167	1.261	1.380	
$\tan C$	0.467	0.661	0.855	
$\tan D$	0.700	0.700	0.700	Arbitrary Selection.
$\tan E$	0	0.100	0.175	
A degrees	0	5.7	9.9	
B degrees	49.4	51.6	54.0	
C degrees	25.0	33.4	40.5	
D degrees	35.0	35.0	35.0	
E degrees	0	5.7	9.9	

From tests of blades in cascade, which are well known to blade designers, it is possible to pick on the blade profiles which when appropriately spaced and placed at the correct chord angle will give the desired fluid outlet angles for the above example and will engage the fluid at inlet without shock.

The blades are spaced sufficiently close to avoid the lift coefficient becoming so great as to stall the blades. A convenient definition of lift coefficient is given by the theoretical coefficient C_L corresponding to the fluid deflection but neglecting losses. This coefficient is given by

$$C_L = 2S/C (\tau L - \tau M) \cos N$$

Where L and M are the inlet and outlet fluid angles respectively, S is the circumferential spacing and C the blade chord, the latter being the

distance between the leading and trailing edges of the blade. The angle N is given by

$$\tau N = \frac{1}{2} (\tau L + \tau M)$$

The desirable values of C_L for design vary considerably with the type of profile used and the condition of operation, such as Mach number; so it is preferable to use cascade test data for determining the spacing. However, present day design values for C_L at the mean radius appear to be given approximately by the following formula.

$$C_L \left(\frac{V_L}{V_M} \right)^y = x$$

Where V_L and V_M are the inlet and outlet fluid velocities respectively and x varies between 1.7 and 2.3. For compressor blades, that is when V_L is greater than V_M , y varies between 2.5 and 3.0. For turbine blades when V_L is less than V_M the value of y appears to be about zero, or in other words $C_L = x$ and therefore varies between 1.7 and 2.3. For the above example, relating to a compressor, as hereinbefore described, an appropriate spacing/chord for the rotating blade at mean radius would be about 1.0, the values of C_L and (V_L/V_M) being approximately 0.9 and 1.35 respectively.

The explanation and example previously given have been taken for a compressor stage of two rows of blades. The difference for a turbine stage is simply that the outlet fluid angles A , C and E will normally be of negative sign giving again normally negative values for the peripheral velocities U_0 , U_1 and U_2 and for the work done at the design radius, as with turbines energy is taken from the fluid, while with compressors energy is imparted to the fluid.

In the typical example above described the variables whose radial distributions were selected to complete the definitions of the blade forms were the axial velocity profile and the inlet fluid velocity of the second stator blade row, the latter being selected for its influence on compressibility effects. Other possibilities will now be briefly discussed.

Of the various favourable design characteristics which may be aimed at, some of the more important are as follows:

(a) Control of axial velocity distributions: this has already been discussed.

(b) Ease of blade manufacture: simplification of blade shape for this purpose may dictate the radial distribution of one or both the variables at the designer's disposal.

(c) Suppression of detrimental compressibility effects or/and cavitation; this calls for a favourable radial distribution of either the fluid inlet angle or fluid inlet velocity in the case of compressors, or in the case of turbines the fluid outlet angle or outlet velocity. As already mentioned, for high velocities or/and highly compressible flows the Mach number distribution is more important than the actual velocity distribution and is therefore preferably selected.

Specific types of blading, in accordance with the invention, which are designed to meet one or more of the above requirements fall naturally into two main groups:

(A) Those for which (a) control of axial velocity distribution is an over-riding consideration.

(B) Those in which close control of axial velocity distribution is not attempted, but more complete satisfaction of requirements (b) or/and (c) is sought.

Both these groups can be sub-divided into two sub-groups according to whether the blading is intended for a compressor or a turbine.

Within these groups I distinguish thirteen varieties of blade design of especial utility, though it must be understood that this list is not considered to be exhaustive.

In group A, one of the variables selectively determined is the axial velocity whose radial distribution may be either constant (as in the specific example hereinbefore described in detail) or parabolic as hereinbefore mentioned; this leaves one other variable only at the designer's choice, which may be exercised as follows:

15 (1) One blade row (rotor or stator) of the stage has untwisted blades of constant blade section.

20 (2) One blade row (rotor or stator) of the stage has blades of constant chord angle but varying blade section.

25 Varieties (1) and (2) are designed to meet requirement (b) above, ease of manufacture; variety (2) has a better aerodynamic performance than (1).

30 (3) One blade row (rotor or stator) of the stage has constant fluid inlet angle, inlet velocity or inlet Mach number.

35 In (4) the fluid inlet angles, inlet velocities or inlet Mach numbers of both blade rows of the stage at the same radius are equal or in constant proportionality, but the actual radial distributions of any of these variables are not arbitrarily selected.

40 In (5) the radial distribution of fluid inlet angle, inlet velocity or inlet Mach number of one blade row (rotor or stator) of the stage is so selected as to minimise compressibility or cavitation effects at every radial station, e. g. so that the variation of the Mach number is in the sense opposed to the variation of thickness of section, i. e. the highest Mach number is associated with the thinnest section and conversely.

45 Varieties (3), (4) and (5) belong to the "compressor" sub-group and varieties (6), (7) and (8) belonging to the "turbine" sub-group are similar to (3), (4) and (5) respectively but with the word "outlet" substituted throughout for "inlet."

In group (B) are varieties (9) to (13), defined as follows: (9) is similar to (2) but the limitation of constant chord angle is applied to the blades of both rows. (10), (11), (12) and (13) correspond respectively to (3), (5), (6) and (8) but the stated limitations on fluid angles, velocities and Mach numbers are applied to both rows of blades; in varieties (10) and (12), the constant values imposed on the fluid inlet or outlet angle, inlet or outlet velocity or inlet or outlet Mach number are not necessarily the same for both blade rows.

50 Varieties (10) and (11) belong to the "compressor" sub-group and (12) and (13) to the "turbine" sub-groups. Varieties (1), (2) and (9) are applicable either to turbines or compressors.

55 The foregoing sets out the manner in which typical blade formations are obtained, but it will be understood that these may with advantage be slightly modified in practice for manufacturing or stress reasons, e. g. to give linear twists, linear tapers in chord or/and thickness, straight leading or/and trailing edges or straight line development between two arbitrarily selected radial stations of the blade, to enable the blades to be withdrawn from dies without splitting the dies.

What is claimed is:

1. A rotary turbine type power conversion machine for use with a compressible viscous working fluid, including at least one rotative row of axial flow type blades having leading and trailing edges, said blades being so shaped and so operatively positioned that the angles of the blades at said edges are varied along the blades to conform to a fluid flow across said row of blades, in which flow the local magnitudes at each radial distance from the axis of rotation of said blade row of the peripheral components of the absolute fluid velocities before entering and after leaving said blade row respectively differ by an amount substantially inversely proportional to said radial distance, being themselves related to said radial distance otherwise than in inverse proportionality.

2. A rotary turbine type power conversion machine for use with a compressible viscous working fluid, including at least two consecutive and coaxial rows of axial flow type blades having leading and trailing edges, whereof one row at least is a row of rotative blades, all of said blades being so shaped and so operatively positioned that the angles of the blades at said edges are varied along the blades to conform to a fluid flow across each of said rows of blades, in which flow the local magnitudes, at each radial distance from the common axis of the blade rows, of the peripheral components of the absolute fluid velocities before entering and after leaving the concerned blade row respectively, differ by an amount substantially inversely proportional to said radial distance, being themselves related to said radial distance otherwise than in inverse proportionality.

3. A rotary turbine type power conversion machine for use with a compressible viscous working fluid, including at least one rotative row of axial flow type blades having leading and trailing edges, the shapes and operative positions of said blades being characterised by entry and discharge blade angles B and C, at said leading and trailing edges respectively, which angles vary along the blades substantially in conformity with the relations

$$(W_1 \tan B - W_2 \tan C) \cdot r = \text{constant}$$

$$r \cdot W_1 \tan B \quad \text{constant}$$

$$r \cdot W_2 \tan C \quad \text{constant}$$

in which relations r is the radial distance from the axis of rotation of the blade row, the angles B and C being measured from a plane perpendicular to said axis, and W_1, W_2 are the local magnitudes, corresponding to each value of the radial distance r , of the axial components of fluid velocity before entering and after leaving the blade row respectively.

4. A rotary turbine type power conversion machine for use with a compressible viscous working fluid, including at least two consecutive and coaxial rows of axial flow type blades having leading and trailing edges, whereof at least one row is a row of rotative blades, the shapes and operative positions of the blades of the first of said blade rows being characterised by entry and discharge blade angles B and C, at said leading and trailing edges respectively, the blades of the second of said blade rows being similarly characterised by entry and discharge angles D and E respectively, all which angles vary along the blades substantially in conformity with the relations

$$(W_1 \tan B - W_2 \tan C) \cdot r = \text{constant}$$

$$(W_1 \tan D - W_2 \tan E) \cdot r = \text{constant}$$

$$r \cdot W_1 \tan B \quad \text{constant}$$

$$r \cdot W_2 \tan C \quad \text{constant}$$

$$r \cdot W_1 \tan D \quad \text{constant}$$

$$r \cdot W_2 \tan E \quad \text{constant}$$

in which relations, r is the radial distance from the common axis of the blade rows, the angles B, C, D, E are measured from a plane perpendicular to said axis, and W_1, W_2, W_3 are the local magnitudes, corresponding to each value of the radial distance r , of the axial components of fluid velocity, before entering the first blade row, intermediate to two blade rows and after leaving the second blade row respectively.

5. A rotary turbine type power conversion machine as claimed in claim 1, wherein the blades of the mentioned rotative blade row are further so shaped and operatively positioned that the angles of the blades at their leading and trailing edges are varied along the blades to conform to a fluid flow across the said row of blades, wherein the axial component of the velocity of the fluid before entering the blade row is substantially constant at all radial distances from the axis of rotation, the axial velocity component after leaving the blade row being likewise substantially constant at all radial distances from said axis.

6. A rotary turbine type power conversion machine as claimed in claim 2, wherein the blades of at least one of the mentioned blade rows are further so shaped and operatively positioned that the angles of the blades at their leading and trailing edges are varied along the blades to conform to a fluid flow across the said row of blades, wherein the axial component of the velocity of the fluid before entering the blade row is substantially constant at all radial distances from the axis of rotation, the axial velocity component after leaving the blade row being likewise substantially constant at all radial distances from said axis.

7. A rotary turbine type power conversion machine as claimed in claim 1, wherein the blades of the mentioned rotative blade row are further so shaped and operatively positioned that the angles of the blades at their leading and trailing edges are varied along the blades to conform to a fluid flow across the said row of blades, wherein the axial component of the velocity of the fluid before entering the blade row varies with the radial distance from the axis of rotation in such a way that its value is least at the ends of the blade and greatest midway between said ends and at intermediate points is such that, when plotted against said radial distance its values lie substantially on a parabola having its vertex midway between the blade ends, and wherein the axial velocity component of the fluid flow after leaving the blade row varies with respect to the radial distance from the axis of rotation in a similar manner.

8. A rotary turbine type power conversion machine as claimed in claim 2, wherein the blades of at least one of the mentioned blade rows are further so shaped and operatively positioned that the angles of the blades at their leading and trailing edges are varied along the blades to conform to a fluid flow across the said row of blades, wherein the axial component of the velocity of the fluid before entering the blade row varies with the radial distance from the axis of rotation in such a way that its value is least at the ends of the blade and greatest midway between said ends and at intermediate points is

such that, when plotted against said radial distance its values lie substantially on a parabola having its vertex between the blade ends, and wherein the axial velocity component of the fluid flow after leaving the blade row varies with respect to the radial distance from the axis of rotation in a similar manner.

9. A rotary turbine type power conversion machine as claimed in claim 2, wherein the blades of at least one of the mentioned blade rows are further so shaped and operatively positioned that the variation along the blades of the blade angle at their leading edges conforms to a fluid flow across the blade row, of which flow one parameter selected from the angle, the velocity and the Mach number of the flow of fluid relative to the blades before entering the blade row is substantially constant at all radial distances from the mentioned common axis.

10. A rotary turbine type power conversion machine as claimed in claim 2, wherein the blades of at least one of the mentioned blade rows are further so shaped and operatively positioned that the variation along the blades of the blade angle at their trailing edges conforms to a fluid flow across the blade row, of which flow one parameter selected from the angle, the velocity and the Mach number of the flow of fluid relative to the blades after leaving the blade row is substantially constant at all radial distances from the mentioned common axis.

11. A rotary turbine type power conversion machine as claimed in claim 2, wherein the blades of at least one of the mentioned blade rows are further so shaped and operatively positioned that the variation along the blades of the blade angle at their leading edges conforms to a fluid flow across the blade row, of which flow one parameter selected from the angle, the velocity and the Mach number of the flow of fluid relative to the blades before entering the blade row is appropriately related to the blade thickness at every radial distance from the mentioned common axis for minimising the effects associated with one of the following phenomena, namely compressibility and cavitation, at all such radial distances, substantially as herein described.

12. A rotary turbine type power conversion machine as claimed in claim 2, wherein the blades of at least one of the mentioned blade rows are further so shaped and operatively positioned that the variation along the blades of the blade angle at their trailing edges conforms to a fluid flow across the blade row, of which flow one parameter selected from the angle, the velocity and the Mach number of the flow of fluid relative to the blades after leaving the blade row is appropriately related to the blade thickness at every radial distance from the mentioned common axis for minimising the effects associated with one of the following phenomena, namely compressibility and cavitation, at all

such radial distances, substantially as herein described.

13. A rotary turbine type power conversion machine as claimed in claim 2, wherein the blades of both the mentioned blade rows are further so shaped and operatively positioned that the variation along the blades of the blade angle at their leading edges conforms to a fluid flow across the blade rows, of which flow one parameter selected from the angle, the velocity and the Mach number of the flow of fluid before entering the first blade row and relative to the blades thereof is so related to a single corresponding and correspondingly selected parameter correspondingly associated with the second blade row that at all radial distances from the mentioned common axis the ratio of the first mentioned to the second mentioned of said parameters has a constant value, which may optionally be unity.

14. A rotary turbine type power conversion machine as claimed in claim 2, wherein the blades of both the mentioned blade rows are further so shaped and operatively positioned that the variation along the blades of the blade angle at their trailing edges conforms to a fluid flow across the blade rows, of which flow one parameter selected from the angle, the velocity and the Mach number of the flow of fluid after leaving the first blade row and relative to the blades thereof is so related to a single corresponding and correspondingly selected parameter correspondingly associated with the second blade row that at all radial distances from the mentioned common axis the ratio of the first mentioned to the second mentioned of said parameters has a constant value, which may optionally be unity.

15. A rotary turbine type power conversion machine as claimed in claim 2, wherein at least one of the mentioned blade rows has untwisted blades whose cross sectional profile is constant along the blade.

16. A rotary turbine type power conversion machine as claimed in claim 2, wherein at least one of the mentioned blade rows has blades whose chord angle, being the angle between a line joining the leading and trailing edges of the blade at the same radial distance from the mentioned common axis and a plane perpendicular to said axis, is constant along the blade and whose cross sectional profile varies along the blade.

Patent No. 2,426,270.

ALUN RAYMOND HOWELL

It is hereby certified that errors appear in the printed specification of the above numbered patent requiring correction as follows: Column 6, line 71, for "tau" both occurrences, read *tan*; Column 7, line 3, for "tau" three occurrences, read *tan*; column 8, line 45, for "sug-group" read *sub-group*; and that the said Letters Patent should be read with these corrections therein that the same may conform to the record of the case in the Patent Office.

Signed and sealed this 11th day of November, A. D. 1947.
